No. 37,238.

Patented November 22, 1904.

UNITED STATES PATENT OFFICE.

ELLERSON L. BRAINARD, OF DANBURY, CONNECTICUT, ASSIGNOR TO THE BRAINARD & WILSON COMPANY, OF DANBURY, CONNECTICUT, A CORPORATION OF CONNECTICUT.

DESIGN FOR A JEWEL-CASKET OR SIMILAR ARTICLE.

SPECIFICATION forming part of Design No. 37,238, dated November 22, 1904.

Application filed October 28, 1904. Serial No. 230,430. Term of patent 7 years.

To all whom it may concern:

Be it known that I, ELLERSON L. BRAINARD, a citizen of the United States, residing at Danbury, in the county of Fairfield and State of Connecticut, have invented a new, original, and ornamental Design for Jewel-Caskets or Similar Articles, of which the following is a specification, reference being had to the accompanying drawing, forming part thereof.

5 The figure is a plan view of a jewel-casket, showing my new design.

What I claim as new, and desire to secure by Letters Patent, is—

The ornamental design for a jewel-casket, or similar article, as shown.

ELLERSON L. BRAINARD.
